MANUFACTURE OF LIQUID HYDROCARBONS

Walter Kroenig, Ludwigshafen-on-the-Rhine,
Germany, assignor to Standard Catalytic Com-
pany, a corporation of Delaware

Application February 14, 1940, Serial No. 318,831
In Germany January 23, 1939

9 Claims. (Cl. 196—62)

The present invention relates to a process for the manufacture of liquid hydrocarbons from tars, mineral oils or higher boiling fractions thereof.

I have found that hydrocarbon oils containing asphalts, as for example tars or mineral oils, more especially higher boiling fractions of the same, may be cracked so that a substantial part of their constituents which boil above 325° C. under a pressure of 12 millimeters (mercury gauge), for example between 20 and 60 per cent thereof, but no more than 75 per cent, are transformed into Diesel oils, lubricating oils, fuel oils or products readily susceptible to hydrogenation or cracking and which boil above 325° C. under atmospheric pressure; there is no marked increase during this process of those constituents boiling below 325° C. at atmospheric pressure. In practicing this process, the initial materials are heated to temperatures of more than 400° C., preferably from 420° to 470° C., under increased pressure, for example a pressure of up to 150 atmospheres, but preferentially a moderately increased pressure, for example a pressure of up to about 70 atmospheres, for a period of time which varies according to the particular initial material used and must be determined by preliminary experiment; after heating the reaction material is released from pressure into a chamber of equal or a somewhat lower temperature and thereby separated into pitch and vaporous products. The products obtained by condensation from the said vapors, if required, are split up into fractions, preferably by physical means, especially by distillation, advantageously by distillation in vacuo, or by means of selective solvents, or they may be treated with refining agents, as for example sulphuric acid or bleaching earths. With a view to obtaining lower boiling motor fuels they may also by themselves or after splitting up into fractions be subjected to cracking or a cracking destructive hydrogenation or also, with a view to obtaining lubricating oils, to a mild destructive hydrogenation.

During the heating under pressure it is essential that exactly such heating time is applied as shall cause the cracking effect mentioned above. This time is a function of the initial material and of the temperature. Thus, for example, when brown coal low temperature carbonization tar is to be heated to 450° C., 1.5 minutes are needed for the range of from 350° to 450° C.; for a naphthenic mineral oil to be heated to 460° C., 1.5 minutes also are needed for the range of from 350° to 460° C.; for an asphalt-base mineral oil

to be heated to 470° C. 3 minutes are needed for the range of from 350° to 470° C. In calculating the duration of stay no consideration is given to the increase in volume of the initial material due to the heating.

The advantage of the process according to the present invention resides in the fact that Diesel oils, lubricating oils and fuel oils may, depending on the particular initial material selected, be produced without destructive hydrogenation or cracking of the products released from pressure, the said oils being superior in quality to those obtained by subjecting the initial materials directly to a mild distillation. By this latter method a considerably larger amount of asphalt is formed than by the method according to the present invention. In this latter case the asphalts and resins contained in the distillate are in a considerably lower molecular state. By subjecting the products released from pressure to a destructive hydrogenation or a cracking treatment, the throughputs and yields may be materially increased and the catalysts are more active than without the pressure heating and release from pressure in the manner defined.

Among suitable initial materials, in addition to those already mentioned, I may mention high-boiling cracking products, for example of mineral oils, or heavy oils obtained in the destructive hydrogenation of mineral coals, pitch, cracking residues or brown coals low in paraffin wax; specifically I may mention stripper oil, i. e., a heavy oil obtained from the escaping vapors in such destructive hydrogenation. It is advantageous to add to the initial materials light-boiling substances, for example middle oil, benzine, benzene or its light-boiling homologues which may be employed over again in a cycle. Moreover, there may be added products which are obtained during the process itself, as for example hydrocarbons obtained during the release of pressure and condensation. These additions are not required if the initial material already contains sufficient quantities of light-boiling constituents. As an alternative, any low-boiling constituents present in the initial material which are rich in hydrogen, as for example benzene, may be removed and replaced by low-boiling hydrocarbons poorer in hydrogen, as for example benzene.

In practicing the process the initial materials are heated, advantageously in tubes, to a temperature of from about 400° to 470° C. under increased pressure, preferably from about 2 to 50 atmospheres. In order to increase the speed of flow, to avoid deposits and to save additional

substances, as for example brown coal low temperature coke, part of the heated products may be circulated in the tubular system by pumping. Heating may be carried out with the addition of small proportions of gases, as for example hydrogen, water gas, cracking gases, gaseous hydrocarbons, nitrogen, carbon monoxide, carbon dioxide or steam.

The materials so heated are then released from pressure into a vessel, preferably a column, and herein placed under a lower pressure, for example atmospheric or subatmospheric pressure. For this purpose the materials are introduced into the release vessel at a sufficient distance above the lower discharge opening. The release vessel is kept, at least in the neighbourhood of the point where the heated initial material is admitted, at a temperature which is equal to or but slightly lower, say by about 10 to 50° C. lower, than that of the heated initial material. In the vapour space of the vessel there are advantageously arranged baffle plates, bell trays or Raschig rings and/or such substances as bauxite, silica gel or active charcoal. By a proper control of the temperature there is thus easily effected a separation into pitchy residues and vaporous products containing heavy oils. The latter leave at the upper end of the vessel, while the former, being liquid at the temperature prevailing in the release vessel, are discharged at the lower end. The temperature, at the point where the vaporous products leave, is only by about 50 to 70° C. lower than at the point where the initial material enters.

After or shortly before releasing the heated materials from pressure it is advantageous to give them an addition of scavenging gases, especially steam, cracking gases, gaseous hydrocarbons, oxides of carbon or nitrogen or hydrogen, the gases being brought approximately to the temperature of the heated materials, or, if the initial materials are very readily decomposed, to a higher temperature; the gases are added in proportions ranging between about 5 and 50 per cent by weight, calculated with reference to the vapours containing heavy oils leaving the release vessel. The scavenging gases may be supplied at the place where the heated materials are introduced into the release vessel or at the bottom end of the release vessel or at both points simultaneously.

It is of special advantage to practice the pressure heating and the release of pressure under such conditions that the amount of the pitchy residue, which is generally solid at ordinary temperature and fusible, is from about 3 to 15 per cent and that the heavy oil contained in the vapours, which boils above 325° C. under a pressure of 760 millimeters (mercury gauge), still contains at least 3 per cent of constituents boiling above 325° C. under a pressure of 12 millimeters (mercury gauge). When working in this manner, the vapours leaving always contain resins and asphalts having a lower molecular weight than the asphaltic substances of the initial material and causing no inconvenience in the subsequent treatment.

Before or while the initial material is heated it is of great advantage to add to it adsorption agents in a finely divided state; among substances suitable for this purpose I may mention brown coal low temperature coke, active charcoal, silicates, bauxite and bleaching earths, for example fuller's earth, or silica gel, synthetic silicates or similar porous materials or and metal compounds,

especially oxides, sulphides, phosphates or halides of the metals of the second to the eighth group of the periodic system, or organic compounds, preferentially of elements of the fifth to the eighth group of the periodic system. The proportions in which these materials are added vary from 0.1 to 10 per cent.

The vapours containing heavy oils may be treated, if desired after condensation, with adsorption agents of the said kind either in a rigidly arranged or finely distributed condition, preferably at moderate temperatures, or with chemical agents, for example sulphuric acid, or subjected to a refining destructive hydrogenation.

If the products obtained after releasing the pressure-heated materials from pressure be split up into fractions by means of selective solvents, it is advantageous to use solvents having polar groups, as for example phenol, nitrobenzene, furfural, aniline, phenylhydrazine, dichloroethylene, keto acids, alcohols or glycol derivatives, but liquid sulphurous acid, liquid ammonia or liquefied hydrocarbons being gaseous at ordinary temperature, or mixtures of both kinds of solvents may also be employed. The fraction rich in hydrogen, if required after having been dewaxed, for example is a good Diesel oil, while the fraction poorer in hydrogen, to which higher boiling constituents richer in hydrogen may still be added, if desired, is adapted for use as a fuel oil.

Excellent motor fuels and fuel oils are also obtained by splitting the very initial materials with selective solvents and subjecting the fractions richer in hydrogen to the pressure heating and pressure releasing treatment as above. That fraction which does not leave in the vapour state is withdrawn as a residue poor in hydrogen at the bottom end of the release vessel and used as such, if desired. The vapours escaping from the release vessel are then split up into Diesel oil, heating oil and/or lubricating oil by fractional condensation or by condensation and subsequent distillation. It is of advantage to free these fractions of paraffin wax. The fraction poor in hydrogen obtained by splitting up the initial material with selective solvents may be subjected for example to a destructive hydrogenation in the liquid phase, benzines and Diesel oils or also lubricating oils being thus produced. The said fraction may also be processed together with the pitchy residues poor in hydrogen which result during the release of pressure and, if desired, also together with portions of the heavy oil obtained during the release of pressure, to produce motor fuels.

The process according to the present invention may also be applied to the products obtained by the so-called low temperature hydrogenation of tars, described for example in the co-pending U. S. application Ser. No. 159,092, filed August 14, 1937. By subjecting the said products to a pressure heating and pressure releasing treatment according to the present invention a product leaving in a vaporous state is obtained from which a pure paraffin wax may very readily be separated, whereas a small proportion of paraffin wax and resin results as a residue. Also a stripper oil obtained by the destructive hydrogenation of mineral oil may have its properties as a fuel oil substantially improved, for example by depressing its pour point, by the process in accordance with the present invention.

The products obtained by the release of pres-

sure may also for the production of motor fuels of lower boiling point be subjected to a cracking or destructive hydrogenation treatment.

For cracking, the oils obtained by heating and release of pressure may be treated at temperatures for example of from 400° to 550° C., preferably in a vaporous state (without a previous condensation), if required under increased pressure, for example under pressures ranging from 5 to 100 atmospheres or higher, advantageously in the presence of catalysts, as for example the porous substances above referred to, provided, if required, with compounds of metals of the second to the eighth group of the periodic system, for example iron, cobalt, nickel, tungsten, molybdenum, chromium or magnesium, or these metal compounds alone. Synthetically made silicates containing alumina and/or magnesia are especially suitable catalysts. The cracking may be carried out under more rigorous conditions with the production of benzines, or under milder conditions with the production of Diesel oils and benzines, the Diesel oil thus obtained having a specially favourable cetene number. The cracking may also with advantage be carried out with the addition of gaseous hydrocarbons, in which case the presence of hydrogen may have a favourable effect upon the lifetime of the catalyst. The cracking may also be carried out in the presence of hydrogen, without the latter being consumed. The proportions of hydrogen used in this case, however, are smaller than those usual in ordinary destructive hydrogenation. The catalyst may also be passed through the cracking space in equal direction with, or preferably, opposite direction to the vapours to be cracked.

The vapours containing heavy oils may also, if required after a treatment with adsorbing agents, be subjected to a cracking destructive hydrogenation in the presence of appropriate catalysts. Special advantage is gained by adopting for this purpose the so-called catalytic low temperature hydrogenation under pressure. For this purpose the vapours are passed along with hydrogen over catalysts having a hydrogenating action, especially over the oxides or, more preferably, the sulphides of the metals of the sixth to eighth group of the periodic system, for example those of tungsten, molybdenum or iron or mixtures thereof, at temperatures of between 270° and 415° C. under a pressure of 50 atmospheres or more, preferably from 200 to 500 atmospheres or more, the temperature being raised in the reaction zone preferably by 20 to 150°, especially 50 to 110° C. In this case a preliminary treatment with hydrogen at temperatures of from about 200 to 250° C. in the presence of catalysts having a strongly hydrogenating action has proved advantageous. The low temperature hydrogenation may be employed for the manufacture of Diesel oil, lubricating oil and paraffin wax or, after removing the paraffin wax and while recirculating the lubricating oil, mainly of Diesel oil or directly of benzine and Diesel oil. The products resulting in the low temperature hydrogenation may also as a whole be converted into benzines with the aid of hydrogenating catalysts arranged on carriers.

The pitchy residues withdrawn at the bottom end of the release vessel may be used, if required in a diluted state, for road construction or as a fuel, or they may be subjected, if desired together with coal, to destructive hydrogenation or low temperature carbonization. They may also, if required after removing solids by extrac-

tion with pyridine or carbon disulphide, be treated with selective solvents, for example with light-boiling hydrocarbons, such as for instance pentane, heptane, or with liquefied hydrocarbons which are gaseous under ordinary temperature, or with selective solvents for aromatic hydrocarbons, for example liquid sulphurous acid, liquid ammonia or solvents having polar groups.

The accompanying drawings schematically represent several modifications of applicant's process.

The following examples serve to illustrate how the present invention may be carried out in practice, but the invention is not restricted to the said examples.

15 *Example 1 (see Fig. 1)*

A crude mineral oil from northern Germany is freed of benzine by distillation and heated along with 1 per cent of flue dust from a brown coal gas producer to a temperature of 460° C. in tubes 1 and 2 under a pressure of 10 atmospheres. The duration of stay within the range of from 350° to 460° C. amounts to 1.5 minutes. The heated product is then released from pressure in a valve 3 down to 1 atmosphere. Immediately after the said release of pressure 10 per cent by weight of steam (referred to the initial material) heated to 450° C. in a heater 5 are supplied through line 4. The mixture of the pressure released product and steam then passes into an enlarged vessel 6, at the lower end of which another 15 per cent by weight of steam at 450° C. are added through line 7. In the top end of the vessel 6 in which provision is made to prevent radiation of heat by an insulation 8 three bell trays 9 are arranged in superposition. Within the release vessel the temperature drops from 460° C. at the point 10 where the released product enters to 405° C. at the point 11 where the vaporous products leave at the top. At the bottom end of the vessel 6 5.5 per cent (with reference to the crude oil) of a pitchy mass melting at 160° C. and containing the flue dust added are withdrawn through line 12. The fractions leaving in a vaporous state at the upper end of the vessel which amount to 87 per cent of the crude oil, inclusive of the benzine initially contained therein, are condensed in a cooler 13. The waste through gas formation amounts to 0.5 per cent. The condensate contains 27 per cent of constituents boiling up to 325° C. at atmospheric pressure, whereas only 24 per cent thereof were contained in the initial material. By this treatment the amount of constituents boiling above 325° C. in vacuo is lessened from 55 to 27 per cent. The condensate in the cooler 13 product is then separated by distillation in a column 14 into 33 per cent of Diesel oil having a specific gravity of 0.860 and an aniline point of 53° C. and a residue of 54 per cent. The latter is subjected to a distillation in vacuo (6 millimeters (mercury gauge)) in a column 15 up to 350° C. (measured in the sump). There are thus obtained 37.4 per cent (referred to crude oil) of a lubricating oil with a specific gravity of 0.936, a viscosity of 6° Engler at 50° C. and a flash point of 220° C. The vacuum residue amounts to 16.6 per cent (referred to crude oil), possesses a specific gravity of 0.966, a viscosity of 11.5° Engler at 99° C. and a flash point of 312° C.

70 *Example 2*

The vaporous fractions obtained according to Example 1 from the release vessel and amounting to 87 per cent of the crude oil are cracked, without a preliminary condensation, over a synthetically

made aluminum silicate catalyst at 430° C., the throughput being 1 kilogram of oil per hour and per liter of catalyst space.

When passing the initial material once through the cracking zone 29 per cent of benzine are obtained having an octane number of 77. The higher boiling constituents are recycled. The catalyst is reactivated from time to time.

Since the catalyst has its efficiency impaired by the addition of water vapor, a gas resulting from the cracking and which contains gaseous hydrocarbons is used instead of the steam introduced into the release vessel, in an amount of 100 cubic meters to each 1000 kilograms of crude oil.

Example 3 (see Fig. 2)

A low temperature carbonization tar from a brown coal of older supplies which has been freed from light oils and contains 7 per cent of asphalt is heated to 450° C. together with 0.5 per cent of brown coal low temperature coke activated with steam in a tubular heater 1 under a pressure of 10 atmospheres. The heated material is then released from pressure by a valve 2 into an enlarged vessel 3 protected from loss of heat by an insulation and, immediately upon the said release of pressure, 25 per cent by weight of steam heated to 450° C. in a heater 5 are added through line 6 (percentage with reference to initial material). At the lower end of the vessel another 70 per cent by weight of steam at 450° C. are added through line 7. At the lower part of the vessel 5 per cent of residue are withdrawn through line 8. There are obtained, besides 0.5 per cent of gaseous hydrocarbons, 94.5 per cent of a distillate containing 4 per cent of asphalt.

This distillate obtained in cooler 9 is collected in a vessel 10 and supplied to the tubular heater 12 and heated therein to 460° C. under a pressure of 10 atmospheres together with 0.5 per cent of brown coal low temperature coke added through line 13. The product is then released from pressure through valve 14 into an enlarged vessel 15. Into this vessel 10 per cent of steam at 460° C. are introduced through line 16 at the point where the release of pressure takes place, while another 30 per cent by weight of steam were introduced through line 17 at its lower end. From the vessel there are withdrawn 4 per cent of residue through line 18; there is formed 1 per cent of gas. The gases and vapors leave through line 19 and are condensed in a cooler 20. The yield amounts to 95 per cent of a distillate which only contains 0.7 per cent of asphalt.

The initial material contains 45 per cent of constituents boiling up to 325° C. under atmospheric pressure. After the double treatment according to the instant example the proportion of the said constituents has increased to 54 per cent. The constituents boiling above 325° C. in vacuo which amounted to 27 per cent in the initial oil are reduced to 11 per cent after the double treatment.

The distillate obtained after the second heat treatment is stripped of the water contained therein in vessel 21 and passed under a high pressure produced by pump 22 through heater 24 together with 3 cubic meters of hydrogen to each kilogram of distillate added through line 23. Then the heated mixture is passed over a catalyst of iron sulphide and tungsten sulphide arranged in vessel 25 at a temperature of 322° C. and then over tungsten sulphide in vessel 26 while raising the temperature to from 400° to 450° C. The vol-

umes of the two catalysts are in the ratio of 1:2.5.

The product obtained, which contains 15 per cent of hydrocarbons boiling up to 200° C. and 65 per cent of hydrocarbons boiling between 200° and 360° C. and constituents of still higher boiling point, is separated into fractions in column 27. The benzine leaving at the upper part of the column is collected in vessel 28. The middle oil is withdrawn through line 29, whereas the higher boiling constituents are returned to the high-pressure reaction vessel 25 through line 30 and heater 24.

The fraction boiling between 200° and 360° C. is combined with 2 cubic meters of hydrogen to each kilogram of initial material added through line 33 and the mixture is then passed to the hydrogenation vessel 32 by way of heater 31. In the said hydrogenation vessel the material is passed over bleaching earth provided with tungsten sulphide and pretreated with hydrogen fluoride at a temperature of 390° C. and under a pressure of 200 atmospheres. By way of column 34 there is obtained a benzine in vessel 35 having an octane number of 73 (research method).

Example 4 (see Fig. 3)

A low temperature carbonization tar free from light oil containing 7 per cent of asphalt, 45 per cent of constituents boiling up to 325° C. and 27 per cent of constituents boiling above 325° C. in vacuo and 1 per cent of brown coal low temperature coke activated with steam are heated under a pressure of 10 atmospheres with a throughput of 20 kilograms per hour first to 400° C. in a tubular heater 1 of a capacity of 800 cubic centimeters and then to 460° C. in a tubular heater 2 of a capacity of 1000 cubic centimeters. The reaction material is then cooled down to 100° C. in cooler 3 under the same pressure. A liquid product is thus obtained which contains 9 per cent of asphalt, 49 per cent of constituents boiling up to 325° C. under atmospheric pressure and 22 per cent of constituents boiling above 325° C. in vacuo.

This liquid product is then heated to 465° C. in tubular coils 4 and 5 of the aforesaid capacity (1800 cubic centimeters) together with 0.5 per cent of brown coal low temperature coke activated with steam added through line 6, the throughput being 7 kilograms per hour, and subsequently released from pressure by means of valve 7 into an enlarged vessel 8 without cooling to a substantial extent. Into this vessel 10 per cent of steam heated to 460° C. in heater 9 are introduced through line 10 at the point where the release of pressure takes place, while another 30 per cent of steam of equal temperature are introduced at the lower end thereof through line 11. At the lower end of the vessel there are withdrawn 7 per cent of residue through line 12. The loss by gas formation amounts to 0.5 per cent. The vaporous products are withdrawn from the top of vessel 8 through line 36 and condensed in cooler 37. The condensate contains 92 per cent of a distillate containing 0.7 per cent of asphalt, 54 per cent of constituents boiling up to 325° C. under atmospheric pressure and 11 per cent of constituents boiling above 325° C. in vacuo. The last-mentioned distillate is treated as specified in the three last paragraphs of Example 3.

What I claim is:

1. The process for the conversion of a hydrocarbon oil containing asphalt into pitch and a normally liquid hydrocarbon product which comprises heating the initial material to a tempera-

ture between about 400 and 470° C. under a pressure ranging from 2 to 50 atmospheres at such a rate that the time of heating from about 350° C. to the desired maximum temperature amounts to about 1 1/2 to 3 minutes; releasing the pressure; passing the heated material upon pressure release into a vessel; introducing a hot scavenging gas into the release zone thereby maintaining the temperature of the material at not substantially lower temperature than said maximum temperature and separating the material into pitch and vaporous products; controlling the total heating time in such a manner as to cause cracking of a substantial part of the constituents boiling above 325° C. in vacuo to products boiling between 325° C. under atmospheric pressure and 325° C. in vacuo without substantial increase in constituents boiling below 325° C. under atmospheric pressure; and separately withdrawing the pitch and vaporous products from said vessel.

2. In the process as claimed in claim 1 heating the initial material in the presence of a finely distributed adsorption agent.

3. In the process as claimed in claim 1 introducing a scavenging gas into the release zone at about the point where the heated material enters.

4. The process according to claim 1 which com-

prises separating the product which leaves the release zone in a vaporous state, after condensation by distillation in vacuo.

5. The process according to claim 1 which comprises splitting up the product which leaves the release zone in a vaporous state, after condensation, by means of a selective solvent.

6. The process according to claim 1 which comprises separating the heated material, while being released, into from 3 to 15 per cent of pitch and into products leaving in a vaporous state, which products in their heavy oil fraction boiling above 325° C. still contain at least 3 per cent of constituents boiling above 325° C. under a pressure of 15 12 millimeters (mercury gauge).

7. A process according to claim 1, which comprises subjecting the product which leaves the release zone in a vaporous state to a catalytic thermal treatment.

8. In the process as claimed in claim 1 heating the initial material under a pressure of about 10 atmospheres to the desired maximum temperature.

9. In the process as claimed in claim 1 using 25 steam as a scavenging gas.

WALTER KROENIG.
